UNITED STATES PATENT OFFICE.

MARSHALL BIDWELL SARGENT AND ARVID EMANUEL KARLBERG, OF INDIANAPOLIS,
INDIANA, ASSIGNORS TO THE STENOTYPE COMPANY, OF INDIANAPOLIS, INDIANA.

TYPE-WRITING MACHINE.

1,119,644.

Specification of Letters Patent.

Patented Dec. 1, 1914.

Application filed July 2, 1914. Serial No. 248,618.

To all whom it may concern:

Be it known that we, MARSHALL B. SARGENT and ARVID E. KARLBERG, citizens of the United States, and residents of Indianapolis, in the county of Marion and State of Indiana, have invented certain new and useful Improvements in Type-Writing Machines; and we do hereby declare the following to be a full, clear, and exact description of the invention, such as will enable others skilled in the art to which it appertains to make and use the same.

This invention relates to improvements in typewriting machines and more particularly to the universal bar or frame construction and its relation to the mechanism with which it co-operates,—one object of the invention being to reduce the length, force and pounding effect of the stroke of the key and actuated means which control the operation of said universal bar or frame.

A further object is to provide a universal bar or frame structure which shall be operated by the key levers in proximity to the fulcrums of the latter and to so mount an engaging or abutment pad that it may be readily adjusted or renewed.

With these and other objects in view, the invention consists in certain novel features of construction and combinations of parts as hereinafter set forth and pointed out in the claims.

In the accompanying drawings, Figure 1 is a sectional view, partly in elevation, showing a stenographic typewriting machine embodying our improvements. Fig. 2 is a partial transverse section, with the universal bar or frame structure shown in front elevation, and Figs. 3 and 4 are detail views.

Fig. 1 represents the frame of the machine, on which a platen 2 is mounted in position to receive the impact of type carried by type levers 3. The type levers are pivotally mounted between their ends upon a notched support 4 and the lower ends of said type levers are pivotally connected with the upper ends of arms 5 which project upwardly from key-levers 6, the latter being mounted in proximity to their rear ends upon a rod 7 passing through a notched support 8 located between the sides of the frame near the rear portion of the latter. Paper feeding means 9 are located on the frame in rear of the platen and inking ribbon mechanism 10 is mounted in the front portion of the

frame, suitable guiding devices being also provided for directing the movements of the paper and inking ribbon between the type and the platen.

A universal frame 11 is mounted on the rod or shaft 7, and comprises uprights 12—13 connected at their lower ends by a cross-bar 14 (which may be termed the universal bar *per se*) and connected at their upper portions by a cross-bar 15, which latter may consist of two horizontal arms projecting toward each other and provided with ears 16 through which a bolt 17 passes. The ears 16 are spaced apart to accommodate a pawl 18 which is loosely mounted on the bolt 17 and serves to actuate the ink-ribbon mechanism when the universal frame is rocked by the actuation of a key-lever.

The lower ends of the uprights 12—13 are bent forwardly and extend below the plane of the rod or shaft 7, so that the universal cross-bar 14 shall be disposed horizontally under the key-levers slightly in advance of the pivotal mountings of said key-levers. A plate 19 is located over the cross-bar 14 and constitutes a holder for a pad 20 to be engaged by the ground lower faces or edges of the key-levers. The plate 19 is supported over the cross-bar 14 by means of a plurality of screws 21 which pass upwardly through the cross-bar. By means of these screws, the pad may be readily adjusted with relation to the key-levers, and said pad and its holder may be prevented from lateral displacement by means of screws 22 passing through the uprights of the universal frame and engaging the ends of the plate or pad holder. The various screws 21—22 are provided with lock-nuts 23 to insure the retention of the pad and its holder in the positions to which they may be adjusted.

An arm 24 having a bifurcated lower end is secured to the lugs 16 of the upper cross-bar of the universal frame, and through the upper portion of this arm, a screw 25 passes horizontally, the head of said screw constituting an adjustable stop to engage a fixed stop 26 carried by the frame of the machine, for limiting the throw of the universal bar 105 when actuated by the key-levers, said universal bar being returned to and maintained in its normal position by the action of a spring 27. The key levers 6 are maintained in and returned to their normal position by 110

the action of springs 28, and are limited in their return movements by engagement of the lower-ends of the type-levers with an adjustable padded stop 29.

5 The universal frame is provided at one side with an arm 30 which projects upwardly above the upper cross-bar 15 and with this arm one end of the spring 27 may be connected, the other end of said spring being attached to the frame 1. The arm 30 is connected, by means of a link 31 with an arm 32 of the paper feeding mechanism. The link 31 is constructed so as to yield lengthwise under abnormal resistance in the operation of the paper feed devices. For this purpose, the pitman may consist of a closely coiled spring. The spacing key 33 is connected by key-bars 34 with upright links 35 pivotally mounted at their lower ends upon the rod or shaft 7. The upper ends of the links 35 are pivotally attached to the lower ends of links 36, the latter being pivotally mounted at their upper ends in the notched support 4 and at their lower ends, engage 25 the adjustable stop 29.

Padded abutments 37 are secured to the links 35 near their juncture with the links 36 and are adapted, when the spacing key is depressed, to engage adjustable abutments 38 carried by the upper cross-bar 15 of the universal frame and move the latter to actuate the paper feeding mechanism, the inking ribbon being also incidentally operated at the same time. The adjustable abutments 38 may conveniently consist of headed screws passing transversely through the upper cross bar of the universal frame and held in the positions to which they may be adjusted by means of lock-nuts 39.

40 Having fully described our invention what we claim as new and desire to secure by Letters Patent, is:

1. In a typewriting machine, the combination with a frame and key-levers pivotally mounted therein, of a universal rocking frame having a cross-bar under said key-levers, a plate over said bar, a pad on said plate, screws for adjusting said plate and

pad vertically, and means for holding said plate and pad in adjusted position. 50

2. In a typewriting machine, the combination with a frame, printing means, pivotally mounted key-levers for actuating the printing means, paper feeding mechanism, and ink-ribbon mechanism, of a universal rocking frame comprising uprights and upper and lower cross-bars, means pivotally supporting said frame above the lower cross-bar, said lower cross-bar disposed under the key-levers near the mounting of said universal frame, means connected with the upper cross-bar of the universal frame for actuating the ink-ribbon mechanism, and means connecting the upper portion of the universal frame with the paper feeding mechanism. 55 60 65

3. In a typewriting machine, the combination with a frame, printing means, pivotally mounted key-levers for operating the printing means, and paper feeding means, of a universal rocking frame having a lower cross-bar disposed under the key-levers, means connecting said universal frame with the paper feeding mechanism, a space key-lever, a pivoted link to which said spacing key-lever is fixed, an abutment on said link, and an adjustable abutment on the universal frame with which abutment on said link engages to move the universal bar. 70 75 80

4. In a typewriting machine, the combination with a frame, printing means, key-levers, and paper feeding mechanism, of a universal bar co-operating with the key-levers, a longitudinally yielding link connected at one end with the paper feeding mechanism and means connecting the other end of said link with the universal bar. 85

In testimony whereof, we have signed this specification in the presence of two subscribing witnesses.

MARSHALL BIDWELL SARGENT.
ARVID EMANUEL KARLBERG.
